UNITED STATES PATENT OFFICE.

KOH ONO, OF NEW YORK, N. Y.

DESIGN FOR A VANITY-CASE.

50,963.

Specification for Design.

Patented June 19, 1917.

Application filed March 21, 1916. Serial No. 85,745. Term of patent 7 years.

To all whom it may concern:

Be it known that I, KOH ONO, a subject of the Emperor of Japan, residing at #139 West 123rd street, New York city, N. Y., U. S. A., have invented a new, original, and ornamental Design for Vanity-Cases, of which the following is a specification, reference being had to the accompanying drawings, forming part thereof.

Figure 1 is a perspective view of a vanity case;

Fig. 2 is a side elevation; and

Fig. 3 is an end elevation of said case, showing my new design.

As shown in Fig. 1 of the drawings, 1

indicates the body of the vanity case upon one side of which is a comparatively large circular element 2 with a slightly raised flat surface as shown in Fig. 2, and 3 indicates a comparatively small circular element located adjacent to said large circular element and upon the same side of the vanity case. The smaller circular element 3 is also slightly raised from the surface of the vanity case, as shown in Fig. 2.

I claim:

The ornamental design for a vanity case, as shown and described.

KOH ONO.
